TO BUTLER MANUFACTURING COMPANY, OF KANSAS CITY, MISSOURI, A CORPORATION OF MISSOURI

FILTER

Application filed February 15, 1930. Serial No. 428,575.

This invention relates to improvements in filters and refers more particularly to filters adapted to remove solid suspended material from dry cleaning solvents, such filters 5 adapted to be connected into dry cleaning systems, and used to receive the discharge from the washers to separate the dirt and solid material prior to subsequent separation of the materials in solution, such as 10 soap or the like, taken out by chemicals or by distillation. It may also be used as a separate unit in a cyclic dry cleaning system wherein the filter is the sole purifying device.

15 The novelty in the invention lies primarily in the use of a vertical container having a collection chamber in the bottom thereof in which is maintained a relatively stagnant pool where the dirt and spent "filter cake" 20 are accumulated; furthermore, the construction permits of a downward flow of the materials in their passage through the filter and an arrangement of vertical leaves connected to a manifold near the bottom of the housing 25 or casing which produces a more uniform deposit of the "filter aid" upon the leaves, distributing the fine and coarse particles uniformly and eliminating the accumulation 30 of the "filter aid" upon the leaves in pear-shaped deposits, thus producing more efficient operation and bringing into effect the entire surface of the individual leaves for the filtering action. This construction permits 35 flushing out the spent "filter cake" and dirt from the bottom chamber of the filter without disturbing the solvent in the upper portion of the filter surrounding the filter leaves.

40 In the drawing Figure 1 is a perspective view of my device showing portions of the casing broken away; Figure 2 is a horizontal section taken about midway the top and bottom of the device; and Fig. 3 is a vertical section taken through the pipe 15 and transversely thereto showing the mounting of the filter leaf on the conduit 15.

45 Referring to the drawing, the filter consists of a housing or cylindrical casing 1 positioned upon legs or standards 2. The 50 top edge is grooved to receive a head 3 which

makes a pressure-tight joint with the top of the housing. This housing is held in place by means of a plurality of clamping screws 4 pivoted to lugs 5 extending out from the housing, and hand wheels 6 which are 55 screwed onto the clamping bolts 5 and contact the outer flange of the head. In order to facilitate the removal of the head an arm 7 is attached to the center of the head and is pivoted on an upright bar 8 to the lower 60 extremity of which is affixed a rack 9. This upright bar or stanchion may be raised and lowered by means of a handle 10 operating a gear within the casing 11 which meshes with the rack 9. A support member 12 is 65 affixed to the side of the housing and holds the upright bar 8 and gear casing 11.

A hand hole plate 13 held in position by a yoke 14 serves as a clean-out opening for the bottom of the filter and may be used to 70 supplement the flushing operation herein-after described.

75 Through the filter container or casing, somewhat above the bottom thereof, extends a discharge manifold 15, and in this discharge manifold are a plurality of openings which are bored with a shoulder such as shown in Fig. 3 to receive the slip joint nipple 16 which is attached to the bottom of each one of the filter leaves.

80 The filter leaves as shown in Figs. 1 and 2 are a plurality of plates consisting of an outer frame 17 which surrounds a central coarse-meshed screen 18 having a finer meshed screen 19 on both sides of the heavier meshed screen. The finer mesh is preferably woven from Monel metal wire or other metal which is non-corrosive to moisture or acid. As suggested, the slip joint nipples by means of which the leaves are positioned 85 in the manifold are attached to the metal of each leaf along the bottom edge of the frame. The leaves are of the same height and vary in width according to their position within the cylindrical casing.

90 Entering at the back of the filter is an inlet pipe 2 which divides itself into a Y within the filter casing, the ends of the Y being upturned to form the stand pipes 21 and 22. At the bottom of the filter is a 95 100

discharge pipe 23 controlled by a valve 24. Also connected into the casing below the manifold 15 are two pipes, one a solvent or sludge drawoff pipe 25 and the other a water inlet pipe 27 regulated by a valve 28.

In operation the filter is hooked into the reclaiming portion of a dry cleaning system so that the discharge from the washer is connected to the inlet pipe 20. The discharge pipe 15 from the manifold is connected back to the washer to return clean solvent back to the washer or to a clarifier or still by means of which the solvent is relieved of materials in solution. There is added to the cleaning solvent a material known as a "filter aid" in the art, consisting of diatomaceous earth or other finely divided material which is carried along in suspension in the solvent and is deposited in the form of a layer upon the surfaces of the filter leaves. The solvent with this material in suspension passes through the inlet pipe 20 and is discharged into the top of the filter through the pipes 21 and 22. When the filter has been filled with liquid the liquid solvent, due to the pressure of the incoming solvent, will be discharged by passing through the fine screens and thence through the discharge nipples 16 into the manifold 15. In passing through the filter leaves a layer or filter cake will be deposited upon each of the leaves of the filter.

When the filter leaves have been given what is known as a "pre-coat" of filter aid material, the filter is then ready to be used in the system, the circulation up to this time being merely for the purpose of depositing the filter aid upon the leaves of the filter. After a batch of garments has been washed in the washer the dirty or soiled solution containing deleterious matter including dirt, thread and particles of miscellaneous substances in suspension, is carried with the solvent into the filter and there deposited upon the leaves of the filter with the filter aid. This operation is continued with successive batches of garments, a filter being connected with one or more washers, according to its capacity. In this way the filter cake gradually builds up on the outer surface of the leaves of the filter and in time the accumulation will fill up the space between the leaves. This may be ascertained by the increase in pressure which is necessary to cause the solvent to pass through the filter. When this pressure becomes excessive, the filter may be cut out of the system, the top removed and the leaves scraped by means of a narrow hoe-shaped instrument which passes down between the leaves and removes the cake from the outside surface of the leaves, permitting it to gravitate to the bottom of the container, or what is termed the "spent cake chamber" of the filter. This removal of the filter cake is re-

peated from time to time as is necessary until the filter aid and dirt scraped from the leaves accumulates in the spent cake chamber of the filter to such an extent that it is built up to the bottom of the leaves. At this time the filter is again cut out of the system by valves on the inlet and discharge pipes after which the valve 24 in the waste line 23 is opened and water under tap pressure is introduced through the pipe 27 by manipulating the valve 28. This water flushes out the dirt and filter cake which has accumulated in the bottom of the chamber without disturbing the solvent which stands in the filter above the manifold 15. The introduction of the flushing water may be by means of a spray nozzle at the end of the pipe within the container, which will spray the entire inside surface of the chamber. When this accumulated filter cake and dirt has been eliminated from the bottom of the filter the valve 28 is closed and the valve 29 in the relief line 30 connected into the housing near its closing is opened, which permits air to pass into the container, draining out through the bottom waste pipe 23 the water used for flushing out the filter cake. When this water and dirt has been discharged, the valve 24 is again closed and additional solvent is added through pipe 20 to fill the filter, valve 29 being open. Valve 29 is then closed and the filter is again ready to go into operation. A pressure gauge 31 is connected into the side of the filter to designate the pressure maintained thereon at all times.

It is recognized that heretofore it has been common practice to remove suspended material from solvents by means of leaves connected into a manifold in this manner, but the arrangement by means of which the solvent is circulated downwardly through a container with a spent filter cake chamber below the leaves of the filter and positioned so that the filter cake and dirt may be flushed out of the filter without disturbing and draining the solvent, afford an operation not heretofore contemplated in dry cleaning systems. The down flow system serves to evenly distribute the filter aid upon the leaves of the filter without accumulating the pear-shaped deposits as it usually does where the up flow arrangement is used.

By introducing the solvent at the top of the filter there is eliminated agitation of the dirty solvent which accumulates in the bottom where the stagnant filter aid accumulates with the dirt scraped from the leaves.

The solvent sludge drain 25 is connected into the filter just below the manifold in order that the solvent may be drained from the filter without disturbing the filter cake accumulated in the bottom of the filter. The hand hole plate 13 is unnecessary normally to remove the filter cake which can readily be flushed from the chamber. It is, however,

supplied in order that the chamber may be scraped in case any dried cake should accumulate which could not be flushed by the introduction of water.

5 While the invention has been drawn primarily to the use of a filter of this type in the filtering of suspended material from dry cleaning solvents, the construction also 10 contemplates its use in any type system where suspended materials are to be separated from liquids.

We claim as our invention:

1. A filter comprising in combination, a container, a removable, pressure-tight head, 15 a plurality of spaced filter screens disposed within said container, comprising triple ply screen leaves, the central screen being coarse in texture and adapted to support finer mesh outer screens, said screens being made of 20 Monel metal or similar non-corrosive metal, frames supporting said filter screens, fittings adapted to permit the passage of liquid

therethrough secured to said frames, and communicating with the inter-screen area, an outlet manifold positioned substantially diametrically across within and at the lower end of said container adapted to support 70 said screens and provided with seats for said fittings, an inlet pipe for the fluid to be filtered, a standpipe positioned within said container and communicating with said inlet pipe, said standpipe having an outlet in 75 the upper portion of said container, whereby the flow of liquid is downward whereby agitation of the sediment is precluded and an even distribution of a filter aid is effected.

2. A filter as in claim 1 including in combination a drain for withdrawn sediment which collects in the bottom of said container and a flush pipe for washing out said filter bottom. 80
